BODY CONSTRUCTION

Emil H. Piron, New York, N. Y., assignor to Transit Research Corporation, New York, N. Y., a corporation of New York

Application June 17, 1943, Serial No. 491,212

6 Claims. (Cl. 105—401)

This invention relates to the construction of vehicle bodies and more particularly to bodies such as are used in street cars and the like. The principal object is to provide a body construction of the general type shown and described in the application of William T. Rossell, Serial Number 434,247, filed March 11, 1942, and to improve that construction from the standpoint of facility of manufacture and ease of maintenance.

In a public vehicle body the conventional arrangement is side-by-side seating with an aisle separating the seats. Since the width of the body is necessarily limited it is highly desirable to make available for passenger use all possible space between the outside walls of the body. It has been found that the comfort of passengers is increased if additional shoulder room is provided above an arm rest and it is the principal object of this invention to provide a vehicle body having a very narrow cross-section above the level of arm rests in combination with a novel and improved construction and arrangement of windows.

In the construction illustrated in the above mentioned Rossell application there is a main window opposite each seat which, when closed overlaps a small fixed window. If the main window is partially elevated air but not rain can enter the passenger compartment. The drawback to the arrangement is that the windows are difficult to wash and that dirt collects between them. It is an object of this invention to provide a thin wall section, a small stationary window thereabove, and a main window capable of being raised and lowered together with means for preventing entry of rain while still admitting air, and to so arrange the windows that both can be washed on their exterior surfaces by mechanical washing machines as are conventionally used for street cars and the like.

More specifically it is the object to provide a small stationary window the top of which may serve as a window sill and an elevatable window sash thereabove having a rain guard forming the lower edge of the sash and adapted to rest directly on the sill.

Other objects and advantages will become hereinafter more fully apparent as reference is had to the accompanying drawings in which my invention is illustrated by way of example and in which

Figure 1 is a vertical, fragmentary section through a car body taken through the floor and extending upwardly above the level of a seat,

Figure 2 is an extension of the same section as

Figure 1 illustrating the arm rest, the fixed window and the lowermost portion of the movable window.

Figure 3 is a further extension of the same section as Figures 1 and 2 illustrating the remainder of the movable window and also illustrating, in elevation, the window lifting mechanism thereabove.

Figure 4 is a horizontal section taken along the line 4—4 of Figure 3, and

Figure 5 is a horizontal section taken along the line 5—5 of Figure 2.

More particularly, 1 refers to the floor of the vehicle body above which extends the body side walls which are composed of an inside wall 2 and an outside wall 3 secured to the inside and outside, respectively, of a series of vertical posts 4. The two walls diverge toward the floor 1 to form an air duct 5. Secured to the inside wall 2 at appropriate height and by a bracket 6 is a seat 7 to accommodate passengers. The inside wall extends upwardly past the bracket 6 until it terminates, as illustrated in Figure 2 at an arm rest 8. The outer wall 3 continues upwardly past the arm rest for a distance and is then terminated between each two posts 4 to form window openings. The entire wall thickness of the body above the arm rest thus has a thickness equal only to that of the outer wall portion except that for purposes of appearance, I add a trim strip or belt rail 10 which also terminates at the window opening. A window sash 11 is fixedly secured to two posts 4 by means of screws 5, the lower portion of the sash being channeled at 13 to receive and retain the belt rail 10 and wall portion 9. The upper portion of the sash 11 serves as a sill for a vertically movable window sash 14.

A drip rail 15 extends outwardly of the sash 14 to a distance vertically above the outermost edge of the belt rail, and downwardly by an amount sufficient to cover the frame, but not the pane, of the sash 11. The drip rail terminates in a sealing surface 16 which rests directly upon the sash 11. Each sash 14 slides up and down in channels 17 secured to or formed with the posts 4. Any suitable device such as an overhead crank 18 may be used to aid in the elevation of the windows.

Various changes may be made without departing from the spirit of my invention, as for instance the wall portion 9 may be lined with paint or cloth or fiber board or the like, and I therefore desire to be extended protection as defined by the appended claims.

What I claim is:

1. In a car body side wall construction, an outside wall, a series of vertical posts to which said wall is secured, an inside wall covering said posts to a height above a passenger seat and terminating at an arm rest, a portion of said outside wall above said arm rest being exposed to view interiorly of the body, a window sash fixed in said portion and retained between two of said posts, and a vertically movable window sash above and in the plane of said fixed sash, the top of said fixed sash comprising the sill for said movable sash.

2. In a car body side wall construction, an outside wall, a series of vertical posts to which said wall is secured, an inside wall covering said posts to a height above a passenger seat and terminating at an arm rest, a portion of said outside wall above said arm rest being exposed to view interiorly of the body, a window sash fixed in said portion and retained between two of said posts, and a vertically movable window sash above and in the plane of said fixed sash, said vertically movable sash having an extension thereon which projects outwardly from the car body as a rain guard and which terminates inwardly in a sealing ledge adapted to rest directly on the lower sash.

3. In a car body side wall construction, an outside wall, a series of vertical posts to which said wall is secured, an inside wall covering said posts to a height above a passenger seat and terminating at an arm rest, the wall covering said posts to a height above a passenger seat and terminating at an arm rest, the wall above said arm rest being of reduced thickness and substantially equal to the thickness of said outside wall, a belt line trim strip outwardly of the wall section above said arm rest terminating therewith to form a window opening between each two of said vertical posts, a fixed window sash secured between each two vertical posts and secured against said trim strip and said wall section, and a vertically movable window sash above and substantially in the plane of said fixed sash, the top of said fixed sash serving as the sill for said movable sash.

4. In a car body side wall construction, an outside wall, a series of vertical posts to which said wall is secured, an inside wall covering said posts to a height above a passenger seat and terminating at an arm rest, the wall above said arm rest being of reduced thickness and substantially

equal to the thickness of said outside wall, a belt line trim strip outwardly of the wall section above said arm rest terminating therewith to form a window opening between each two of said vertical posts, a fixed window sash secured between each two vertical posts and secured against said trim strip and said wall section, a vertically movable sash above and in the plane of said fixed sash, the lower position of said movable sash having a drip rail extending outwardly and downwardly therefrom and terminating inwardly in a portion adapted to contact the upper part of said fixed sash.

5. In a car body side wall construction, an outside wall, a series of vertical posts to which said side wall is secured, an inside wall covering said posts to a height above a passenger seat and terminating at an arm rest, the wall portion above said arm rest having the substantial thickness of said outside wall only, a belt line trim strip covering said wall portion and terminating therewith to form a window opening thereabove and between each two of said posts, a window sash fixed between each two of said posts and having its lower edge channelled to receive and retain said trim strip and said wall portion, and a vertically movable sash immediately above said fixed sash and adapted to close thereagainst, said movable sash having a drip rail extending outwardly and downwardly therefrom and overlapping the frame portion of said fixed sash.

6. In a car body side wall construction, an outside wall, a series of vertical posts to which said side wall is secured, an inside wall covering said posts to a height above a passenger seat and terminating at an arm rest, the wall portion above said arm rest having the substantial thickness of said outside wall only, a belt line trim strip covering said wall portion and terminating therewith to form a window opening thereabove and between each two of said posts, a window sash fixed between each two of said posts and having its lower edge channelled to receive and retain said trim strip and said wall portion, and a vertically movable sash immediately above said fixed sash and adapted to close thereagainst, said movable sash having a drip rail extending outwardly of the car body for a distance substantially the same as said trim strip and also downwardly by an amount sufficiently to cover the top frame of said fixed sash without covering the pane thereof.

EMIL H. PIRON.
